UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

ERASER-HOLDER.

1,250,227.

Specification of Letters Patent. Patented Dec. 18, 1917.

Application filed January 21, 1915. Serial No. 3,592.

To all whom it may concern:

Be it known that I, ALVAH C. ROEBUCK, a citizen of the United States, residing at Woodstock, in the county of McHenry and 5 State of Illinois, have invented certain new and useful Improvements in Eraser-Holders, of which the following is a specification.

This invention relates to a container or holder for erasers, more particularly for 10 round erasers commonly used by typewriting operators, although, of course, it may have a general application wherever similarly employed.

The principal object of the invention is to 15 provide a holder of this class particularly adapted to be used in connection with typewriting machines.

Further objects will be hereinafter set forth.

20 In the drawing, Figure 1 is a plan view of a portion of a typewriter frame to which an eraser holder, constructed in accordance with the principles of this invention, is attached; Fig. 2 is a side elevation of the same, Fig. 3 25 is a perspective of the holder proper and Fig. 4 is a modification.

Typewriter operators generally use an eraser circular in form to make corrections in their work while it is still in the machine, 30 and the most convenient place for keeping the eraser is on the frame of the machine where it can be easily found and quickly used and replaced. One of the great objections to this use is that the centers of such 35 erasers are commonly provided with metal side disks which soon scratch the frame of the machine and quickly mutilate the japan, thus giving the machine an unsightly appearance. Another objection to placing the 40 eraser on the frame of the machine is that the successive impacts caused in writing soon jar the eraser from the frame, causing much annoyance in finding and replacing it where it is convenient for use. The present invention 45 relates to a simple holder for erasers of this kind which is intended to be applied to the frame of a typewriting machine in which an eraser can be deposited after use, and from which it cannot be dislodged by ordinary 50 impacts in the machine.

In the drawing, the numeral 5 designates, generally, the frame of a typewriting machine, more particularly the top plate at the side of such machine which has a horizontal 55 surface, and in some types of machines is

provided with a ribbon spool holder 6. Adjacent and in front of the ribbon spool holder 6 is a space upon which an eraser may be placed and to which a holder designated generally by the reference numeral 7, 60 may be applied. This holder comprises a flat base portion in which is a perforation 8 with a forwardly extending tongue 9 which is rounded upwardly at its forward end to form a forward projection above the plane 65 of the base. At the rear the holder is formed with a perforated tongue 10 and extending between the tongues 9 and 10 at the edges of the plate are upright sides 11 which are curved inwardly at the rear but are separated 70 by the tongue 10.

This holder is secured to the frame by means of fastening screws 12 which extend through the perforations 8 and 10 into the frame, and interposed between the base of 75 the holder and the frame is a pad 13 of non-abrasive material, such as felt or the like, to prevent the holder from scratching the frame.

In using the holder, an eraser of the class 80 to which the holder applies, is simply placed in the holder, as shown by the dotted outline 14 in Figs. 1 and 2, and the eraser usually projects slightly beyond the curved portion of the tongue 9 so that it may be readily 85 grasped by an operator for use. When in the holder the eraser is prevented from dislodgment because of the sides 11, and by reason of the fact that the upwardly projecting tongue holds the eraser at such an angle to 90 the horizontal that it cannot be dislodged from the holder by the ordinary impacts due to the operation of the machine.

The rim or upward projection of the holder might be continued unbroken from 95 one side to the other at the rear as shown by Fig. 4, having a rim 15, and the holder held in place on the frame by two or more screws placed inside of the holder through opening 16, but it has been found more convenient to 100 have an opening at the rear of the holder for the passage of the finger of the operator to assist in quickly and conveniently dislodging an eraser in the holder.

What I claim is:

1. An eraser holder composed of a single piece of sheet material having a flat base with a front tongue raised at the outer end and with upstanding sides curved rearwardly to receive a round eraser therein, the 110

tongue tipping an eraser upwardly at the front and against the sides to prevent its dislodgment from the holder.

2. A holder for a round eraser having a flat base adapting it to be secured to a horizontal surface and with upturned sides curved rearwardly, and a raised front portion to hold an eraser inclined downwardly against the upturned sides to prevent its accidental dislodgment, said holder being substantially round and but slightly larger than an eraser which it is to contain.

3. An eraser holder composed of a single piece of sheet material having a flat base with an upwardly projecting front tongue and upstanding curved sides to accommodate and closely contain a round eraser, and with a space at the rear between the sides for the insertion of a person's finger to assist in removing an eraser therefrom.

4. The combination with a typewriter having a frame portion with a horizontal sur-

face, of an eraser holder comprising a single piece of sheet material having a flat base with an upwardly projecting front tongue and lateral upright sides extending from the front tongue about the edge but spaced apart at the rear, and a perforated tongue at the rear between the ends of the upright portions, another perforation being provided in the body of the holder and a non-abrasive substance disposed between the holder and the frame, and means for fastening the holder to the frame through said perforations in the tongue and body of the holder.

In testimony whereof I have signed my name to this specification, in the presence of two subscribing witnesses, on this 16th day of January A. D. 1915.

ALVAH C. ROEBUCK.
